SPRAYER

Erik Sigfrid Lynger, Stockholm, Sweden, assignor
to Electrolux Corporation, Dover, Del., a cor-
poration of Delaware

Application January 25, 1933, Serial No. 653,452
In Germany February 9, 1932

3 Claims. (Cl. 299—89)

My invention relates to sprayers and particularly to sprayers adapted to be operated by a source of air under pressure. Still more particularly, my invention relates to a sprayer adapted to be operated, for example, by the exhaust of a vacuum cleaner, which produces a large volume of air under a moderate pressure.

My invention will be understood from the following description considered in connection with the accompanying drawing, which forms a part of this specification, and of which:

Fig. 1 is a cross-sectional view of a preferred embodiment of my invention; and

Fig. 2 is a cross-sectional view of a somewhat modified embodiment of my invention.

Referring to the drawing, reference character 10 designates a container adapted to hold liquid. Container 10 may conveniently be a glass jar provided with a threaded top 11. A cover member 12 provided with screw threads is adapted to engage the threaded top 11 of jar 10. A washer 13 of rubber or other suitable material is preferably placed between the top of the jar and the cover member.

Secured to cover member 12, as by welding or soldering, is an air supply tube 14. One end of tube 14 may be enlarged, as is shown at 15, so as to be adapted to receive the end of an air supply conduit 16. The other end of air supply conduit 16 may be connected to the exhaust of a vacuum cleaner, or to any other suitable source of air under pressure. The opposite end of air supply tube 14 is constricted to form an air blast nozzle 17 providing a relatively small air blowing opening. An aperture 18 is formed in the side of air supply tube 14 which is adjacent to cover member 12. A corresponding aperture 19 in alignment with aperture 18 is formed in the cover member so that the two apertures together form a passage from within air supply tube 14 to within jar 10.

A relief tube 20 having a smaller outer diameter than the inner diameter of air supply tube 14 extends through cover member 12 and through the air supply tube and terminates with an outer end in communication with the atmosphere. The inner end of relief tube 20 is in communication with the interior of container 10. There is no direct communication between the interior of air supply tube 14 and the interior of relief tube 20.

A liquid riser conduit 21 extends through, and is supported by, cover member 12 and the side of air supply tube 14 which is adjacent to the cover member. The lower end of conduit 21

is adjacent to the bottom of container 10. The upper end of conduit 21 extends axially within air supply conduit 14 and terminates in a liquid nozzle 22 adjacent to air blast nozzle 17. Liquid nozzle 22 may be removable from conduit 21 and replaceable by other nozzles of different design for spraying different kinds of liquid.

The above described embodiment operates as follows:

In order to fill container 10 with liquid to be sprayed, cover 12 is unscrewed therefrom. Liquid may then be poured into container 10 to any desired height above the bottom of riser conduit 21. The cover 12 is then replaced and air supply conduit 16 connected to air supply tube 14. When air under pressure is supplied through conduit 16 to tube 14, it causes an increase in pressure above atmospheric within tube 14, particularly in view of the constricted air blast nozzle 17. Apertures 18 and 19 permit this pressure to be communicated to within jar 10. However, if relief tube 20 is open to the atmosphere, pressure cannot be built up in container 10 due to the fact that the diameter of relief tube 20 is greater than the diameter of apertures 18 and 19. Under these conditions, air will be discharged through air blast nozzle 17, but no liquid will be discharged through liquid nozzle 22. The sprayer is conveniently held by grasping in the hand both the air supply conduit 16 and the air supply tube 14 in the region where the two are joined. In order to cause liquid to be discharged, the operator places a thumb or finger of the hand holding the sprayer over the outer end of relief tube 20. With the relief of pressure through tube 20 prevented, pressure is built up within container 10 above the liquid therein and forces the liquid to rise through conduit 21 and to be discharged through nozzle 22. The bore of nozzle 22 is small and the fine stream of liquid discharged therethrough is caught up by the surrounding air blast and broken up into a fine spray which is carried along by the air.

In order to stop the spraying action, it is only necessary to remove the thumb or finger from the end of relief tube 20, whereupon pressure within container 10 is relieved and no liquid is forced upwardly through conduit 21 to the nozzle 22.

In Fig. 2 there is shown a modification of the above described sprayer. In this modification the relief tube 20 does not extend through air supply tube 14, but is located to one side thereof. The length of relief tube 20 is preferably sub-

stantially the same as the diameter of air supply tube 14 in order that the upper end of the relief tube shall be approximately on a level with the top of the air supply tube so that a finger 5 or thumb of the same hand which is used to grasp the sprayer may be placed conveniently over the open end of the relief tube. Otherwise than this, the construction of the two modifications is the same. The operation of the modification shown in Fig. 2 is the same as that of the 10 device shown in Fig. 1, whereby it is not necessary to repeat the description thereof.

While I have shown two more or less specific embodiments of my invention, it is to be understood that they are for purposes of illustration only and that I am not to be limited except by the scope of the appended claims viewed in the light of the prior art.

What I claim is:

- 20 1. A sprayer without moving parts comprising a liquid container having an open top, a cover member engageable with said container, an air supply tube secured to and in contact with said cover member, one end of said tube being adapted to be connected to an air supply conduit and to form a hand-grasp member and the other end of said tube being constricted to form an air blast nozzle, a liquid riser conduit extending through, and being supported by said cover member, one end of said riser conduit extending to near the bottom of said liquid container and the other end extending within said air supply tube and terminating in a liquid nozzle adjacent to said air blast nozzle, said air supply tube and 25 said cover member being formed with aligned continuously open apertures in adjacent portions for supplying air to said container, and an unobstructed relief tube extending through said cover member for establishing communication between the interior of said container and the atmosphere, said relief tube having a greater cross-sectional area than the cross-sectional area of said apertures and having an upper opening so located with respect to said hand-grasp member as to be closable directly by the same hand of the operator as is holding said hand-grasp member.
- 30 2. A sprayer without moving parts comprising a liquid container having an open top, a cover member engageable with said container, an air supply tube secured to said cover member, one end of said tube being adapted to be connected to an air supply conduit and to form a hand-grasp member and the other end of said tube being constricted to form an air blast nozzle, a liquid riser conduit extending through, and being supported by said cover member, one end of said riser conduit extending to near the bottom of said liquid container and the other end extending within said air supply tube and terminating in a liquid nozzle adjacent to said air blast nozzle, said air supply tube and said cover member being formed with continuously open aligned apertures in adjacent portions for supplying the air to said container, and an unobstructed relief tube extending from within said container through said cover member adjacent to said air supply conduit and at substantially right angles to the axis thereof for establishing communication between the interior of said container and the atmosphere, the length of said relief tube being substantially the same as the diameter of said air supply tube, said relief tube having a greater cross-sectional area than the cross-sectional area of said apertures and having an upper opening so located with respect to said hand-grasp member as to be closable directly by the same hand of the operator as is holding said hand-grasp member.

liquid riser conduit extending through, and being supported by said cover member, one end of said riser conduit extending to near the bottom of said liquid container and the other end extending within said air supply tube and terminating in a liquid nozzle adjacent to said air blast nozzle, said air supply tube and said cover member being formed with aligned continuously open apertures in adjacent portions for supplying air to said container and an unobstructed relief tube extending from within said container through said cover member and through said air supply tube at substantially right angles to the axis thereof for establishing communication between the interior of said container and the atmosphere, said relief tube having a greater cross-sectional area than the cross-sectional area of said apertures and having an upper opening so located with respect to said hand-grasp member as to be closable directly by the same hand of the operator as is holding said hand-grasp member.

3. A sprayer without moving parts comprising a liquid container having an open top, a cover member engageable with said container, an air supply tube secured to said cover member, one end of said tube being adapted to be connected to an air supply conduit and to form a hand-grasp member and the other end of said tube being constricted to form an air blast nozzle, a liquid riser conduit extending through, and being supported by said cover member, one end of said riser conduit extending to near the bottom of said liquid container and the other end extending within said air supply tube and terminating in a liquid nozzle adjacent to said air blast nozzle, said air supply tube and said cover member being formed with continuously open aligned apertures in adjacent portions for supplying the air to said container, and an unobstructed relief tube extending from within said container through said cover member adjacent to said air supply conduit and at substantially right angles to the axis thereof for establishing communication between the interior of said container and the atmosphere, the length of said relief tube being substantially the same as the diameter of said air supply tube, said relief tube having a greater cross-sectional area than the cross-sectional area of said apertures and having an upper opening so located with respect to said hand-grasp member as to be closable directly by the same hand of the operator as is holding said hand-grasp member.

ERIK SIGFRID LYNGER.
